UNITED STATES PATENT OFFICE.

WILLIAM BLACKER, OF STALYBRIDGE, ENGLAND.

APPARATUS FOR BEATING GOLD LEAF OR SHEETS OF OTHER METAL AND SUCH LIKE.

Application filed June 3, 1925, Serial No. 34,595; and in Great Britain January 30, 1925.

This invention concerns an apparatus for beating gold leaf or other precious metals, and such like uses, and concerns the type of machine wherein a power driven hammer 5 pounds the pad or article on the rotatable block and wherein the blows distributed are controlled by mechanism acting on the hammer as the pad moves around on its support.

The novelty has reference to an improved 10 automatic hammer mechanism for the purpose indicated wherein a simple type of cam or profile plate is used to act on and control the movable striking parts of the hammer through a lever structure with movable 15 fulcrum, and to means which allow the said cam to be driven at a variable speed both with the object of controlling the distribution of blows from the hammer upon the pad or equivalent.

20 The attached drawings sufficiently illustrate my improvements, and in the drawings:

Fig. 1 shows a general side elevation of the apparatus with certain of the parts omitted.

25 Fig. 2 is also an elevation taken from the opposite side.

Fig. 3 shows a plan view.

Fig. 4 is a separate detail view.

Fig. 4^a is also a detail view.

30 Fig. 5 shows a front elevation.

Fig. 6 is a rear elevation.

Fig. 7 is a diagram of cam mechanism and parts which co-operate therewith and which are illustrated in other figures.

35 Fig. 8 is a diagram of a square beater's pad and illustrates one way of distributing blows upon said pad as same is rotated.

I make use of a proper base or stand of appropriate design and upon this is mounted 40 a support or rest such as the anvil *a* which has a wooden, rubber or other receiver or recessed face for the beater's pad *P* (which as known is about 5 inches square), and the anvil *a* is so mounted as to be revolvable by driving mechanism. It is shown mounted so as to be capable of rotation or not and is indicated as provided with a bevel wheel *a'* driven by a bevel wheel *a''* mounted on the shaft *b* supported in proper bearings. Any 45 other suitable form of driving gear may be employed to actuate the rotary anvil.

Upon the same base is mounted the mechanical hammer structure which may be of the type illustrated herein, having an arm *c* carrying a tup *c'* in proper position over the pad *P*, the arm *c* fitting a bored slideable

socket *c''* mounted upon two shafts *c³*, *c⁴* connected by links or levers *d*. A swivelling block *d'* having trunnions *d²* is provided, said trunnions engaging holes in the levers *d*, and through a central opening in the block *d'* passes a rod *e* with upper and lower springs *e'*, *e²*, the rod being pivoted at *e³* to a lever *f* fulcrumed at *f'* at the side of the machine, said lever having a slot for regulating the action on the rod *e*. The fulcrumed lever is worked by a connecting rod *f²* from a crank disc *f³* on the main driving shaft *g*. Any other hammer actuating means may be employed which will mechanically 65 swing a hammer head supported upon a carrier arm.

The hammer head *c'* must be movable laterally and it moves on the two shafts *c³*, *c⁴* provided, and as and when required by reason of a pivoted lever *h* (see Figs. 2 and 5) which loosely engages at or near its upper end a bar or slide *i* suitably guided in bearings in the framework. On this bar or slide *i* (see Fig. 7) is mounted a board 80 and turned **H** shaped boss marked *i'* which is confined between two collars *i²*, *i³*. The **H** shaped boss *i'* engages a projection *c⁵* on the lower part of the bored slideable socket *c²*. The connection can be rendered inoperative by unscrewing the studs in the collars *i²*, *i³*. A leather buffer washer *i³* is fitted.

About the centre in the length of the lever *h* (which is fulcrumed at *h'*) interconnection is made by a slide motion conveniently consisting of two guided rods *j*, *j'* and upon which is fixed a cam bowl *j'* which works with a cam or cams, and for preference a cam *k*, the periphery of which can be varied to vary the distribution of blows. The cam may be mounted to permit of ready change. The function of the cam *k* is to control or move the hammer head, and it does this by acting on and through the fulcrum lever *h*. The shape of the cam and lever may vary somewhat to variously affect the range of action. Such fulcrumed lever *h* by its upper end slidably engages and moves the bar or slide *i* and the fulcrumed lever *h* is acted upon by a bowl *j'* carried by the two guided rods *j*, *j'*. The lever *h* has its fulcrum at *h'* upon a movable nut *h²* which engages a vertical screw-threaded shaft *h³* and is additionally guided by a rod *h⁴* (see Figs. 3 and 5) or other slide device, the screw-threaded shaft *h³*, and rod *h⁴* being supported in brackets

105

110

or otherwise. The purpose of the fulcrumed lever h and movable nut h^2 is that they permit alteration in the ratio of distance between the fulcrum h' , the cam k and the rod or slide i , to gradually and automatically add to the amount the hammer head is influenced so as to enlarge the area over which the blows are struck or distributed. The top of the screw-threaded spindle h^3 10 carries a bevel gear h^6 with which gears a second bevel wheel h^7 mounted on a shaft h^8 . This shaft h^8 carries a ratchet wheel h^9 which is periodically actuated by a pawl h^{10} mounted on the bracket h^{11} worked by a 15 connecting rod h^{12} operated by an eccentric h^{13} on the shaft b whereby the nut h^2 is slowly raised. By disengaging the pawl h^{10} and turning backward the hand-wheel h^{14} the nut h^2 may be wound down and the lever 20 h re-set, that is, its fulcrum can be carried down to its initial starting point as in Fig. 5.

The location of the cam or profile plate k is preferably a lateral one and it is shown 25 mounted on the shaft b and actuated by worm gear, a worm wheel k^2 on the shaft b being driven by a worm k^3 on the auxiliary shaft k^4 .

I actuate the cam or profile plate and the 30 rotary anvil through a variable speed gear and in the drawings (Figs. 3 and 6) I illustrate a known simple type of three speed gear. The three fixed wheels p are applied on the auxiliary shaft k^4 which carries the 35 worm k^3 and the three fixable wheels o are applied on the main driving shaft q . A sliding spring key is recessed into the driving shaft q and is operated by the movable sleeve q' from the control lever r fulcrumed 40 at r' . This control lever has a pin r^2 which works to a series of recesses in the bearer r^3 as for instance three recesses. When one or other of the three holes is occupied one or other of the variable speed gears is locked 45 by the slideable spring key (indicated diagrammatically at Fig. 4^a) whilst if an intermediate position be occupied the gears are unlocked all as is shown.

The driving shaft q may be controlled 50 through fast and loose pulleys but I show a clutch device consisting of a slideable clutch belt element s which is moved against a spring to the fixed clutch element s' by a boss s^2 worked by a draw-bar s^3 and connected lever s^4 . This lever s^4 has a projection fitting a recess in the framing. If the draw-bar s^3 be pulled out the projection emerges from the recess, and the boss s^2 pushes the movable half of the clutch into 55 gear. Opposite actuation of the draw-bar s^3 puts the clutch out of gear and so the apparatus stops.

It is apparent that stoppage of the whole 60 apparatus can be effected either by disengagement of the clutch element s or stoppage

of the anvil a only by disengagement of the variable speed gear.

A balance weight n and cord n' keep the fulcrumed lever h up to the bowl j^2 and the bowl j' of the guided rod structure j , j 70 against the edge of the cam k .

Arrangements for locating the blows upon the pad P , that is, as to their distribution can be considerably varied. For example, I may strike 24 blows for one revolution 75 or movement of the anvil a , or 48 blows, or as required and such blows may be struck or distributed in varied pattern according to any known system and over a small area or over a larger area according to requirements 80 as the beating work proceeds, a step by step movement or adjustment of the supported beater's pad or the hammer or both automatically occurring after each blow.

Referring to the diagrams Figs. 7 and 8, 85 there 24 blows are intended to be struck for one round of the beater's pad.

The cam motion is synchronized to move with the anvil. As the lever h is about twice the length of the distance from the fulcrum h' to the bowl j^2 any movement imparted by j^2 to the top of the lever h would be twice the amount due to the action of the segmental rise on the cam. If the cam contour from A to B rises $\frac{3}{4}$ inch then the 90 movement from A to B on the beater's pad would be $1\frac{1}{2}$ inches (see the diagram Fig. 8). From B to C the fall is $\frac{3}{8}$ inch and from C to D the rise is $\frac{1}{8}$ inch and from D to E the fall is $\frac{1}{4}$ inch whilst the rise 100 from E to F is $\frac{1}{4}$ inch. Thus, the distribution of a range of six blows to a quarter of a round are in co-relationship. This explanation covers a quarter revolution of the cam K and the anvil. 105

The cut-away portions h^* may be provided in the lever h to negative all distributive motion on the initial start of the beating or later, it being common practice to first deliver a number of blows in the 110 centre of the beater's pad. As the lever h is raised the blows B are struck, then D and F begin to leave the centre, followed later by C and E, and, as the lever h continues to rise the blows continue to spread over an enlarged area of the beater's pad, but in fixed 115 relationship to each other and as governed by the manner in which the cam and variable speed gear influence the lever h .

It is to be observed that the use of a 120 variable speed gear gives me increased control in the distribution of the blows as with a cam or profile plate having a definite contour the speed of driving the cam is material. If the hammer speed is constant then 125 the speeding up or slowing down of the anvil and cam must of necessity affect the distribution of the blows. A slow speed means the cam exercises the most gradual influence in controlling the location of the tup when 130

it strikes whilst a quick speed means a maximum influence from the cam in a given space of time. If the gear for example be altered from striking 24 blows to strike 12 the effect would be each alternate blow is cut out and only blows A, C, E given. By variation in the gears the range or distribution of the blows is correspondingly changed.

The hammer head, no matter what the scheme of blow distribution may be, always returns to the centre, on the completion of the blow distribution scheme, because the fulcrum h' moves through a truly vertical path and so when the cam or profile plate permits it, the hammer head reverts to the centre and starts again outwards.

It will be understood, the synchronized movement of the beater's pad support and the lateral movements of the hammer head take place whilst the latter is elevated.

I declare that what I claim is:

1. An apparatus of the character described, comprising in combination, a rotatable work support, means for rotating said support, a hammer mounted for vertically swinging and laterally reciprocating movement above said support, means for swinging said hammer, a pivoted lever for imparting lateral motion to the hammer, means for swinging said lever thereby to move the hammer laterally, and means for changing the ratio of distance between the fulcrum of the lever, the point of application of the swinging means and the point of application of the lever thereby to multiply the action of said lever-swinging means.

2. An apparatus of the character described, comprising in combination, a rotatable work support, means for rotating said support, a hammer mounted for vertically swinging and laterally reciprocating movement above said support, means for swinging said hammer, a pivoted lever for imparting lateral motion to the hammer, means automatically operative during the rotation of the work support for changing the ratio of distance between the fulcrum of the lever, the point of application of the swinging

means and the point of application of the lever thereby to multiply the action of said lever-swinging means when transmitted to the hammer for moving it in one direction, and manually operable means for re-establishing the initial ratio of distance between said points for moving the hammer laterally in the opposite direction.

3. An apparatus of the character described, comprising in combination, a rotatable work support, means for rotating said support, a hammer mounted for vertically swinging and laterally reciprocating movement above said support, means for swinging said hammer, a pivoted lever for imparting lateral motion to the hammer, a rotatable cam operated by said rotating means for swinging said lever thereby to move the hammer laterally, and means for changing the ratio of distance between the fulcrum of the lever, the point of application of the cam and the point of application of the lever thereby to multiply the motion imparted by said cam.

4. An apparatus of the character described, comprising in combination, a rotatable work support, means for rotating said support, a hammer mounted for vertically swinging and laterally reciprocating movement above said support, means for swinging said hammer, a pivoted lever for imparting lateral motion to the hammer, a rotatable cam operated by said rotating means for swinging said lever thereby to move the hammer laterally, means for changing the ratio of distance between the fulcrum of the lever, the point of application of the cam and the point of application of the lever thereby to multiply the motion imparted by the cam, and means also operated by the rotating means and automatically operative to impart to said motion multiplying lever a step-by-step increase in its multiplying ratio.

In testimony whereof I have signed my name to this specification.

WILLIAM BLACKER.
